UNITED STATES PATENT OFFICE

2,436,531

CONTAINER CLOSURE

Robert C. Shipley, Kalamazoo, Mich.

Application October 3, 1945, Serial No. 620,022

5 Claims. (Cl. 206—1.5)

1 This invention relates to an improved container closure and is more specifically concerned with such means operable by a single simple movement and having no externally visible parts when the container is closed.

While innumerable means have from time to time been provided for holding containers in a closed condition, relatively few of them are effective and also entirely concealed from external view when the box is closed. Nevertheless, in providing an attractive container for a high grade product, such as a container made from highly polished mahogany, it is desirable that the container not be disfigured when it is in closed position by externally visible hinges, plates, latches or other conventional closure means.

It is further desirable in providing such a closure that it be releasable by a simple manual movement so that the container may be opened or closed with a minimum of effort. However, this ease of operation should not be accomplished by the sacrifice of firm holding when the container is in a closed condition.

Further, where the container is used in the distribution of a high grade article of commerce, such as a finely made shaving razor, so that it will be manipulated with considerable frequency over a long period of time, it is especially desirable that the closure mechanism not only act cleanly and positively but that it have a minimum of moving parts and a maximum of sturdiness and durability.

Therefore, the principal object of this invention is to provide means for maintaining a container in a closed position without recourse to a latch or other conventional means of closure.

Another object of this invention is to provide a means for securing the cover of a container firmly in place by a rapid single movement in such a manner that the cover will remain in that position without slippage.

Another object of this invention is to provide means for securing a container and a cooperating cover firmly together in closed relationship which will conceal from view all elements of the closure means when said parts are in such closed relationship.

Another object of this invention is to provide means as aforesaid which will operate cleanly and firmly and which will have a high degree of durability and resistance to wear and rough usage.

A further object of my invention is to provide closure means as aforesaid which are of such simple construction that the fabrication thereof can be effected rapidly and inexpensively.

2 Other objects and purposes of my invention will be apparent to those acquainted with articles of this type upon inspection of the following specification with reference to the accompanying drawing.

Figure 1 is a side elevation of a top and bottom section of a container provided with my improved closure means.

Figure 2 is a top plan view of one section.

Figure 3 is a bottom plan view of another section.

Figure 4 represents a section taken on the line IV—IV of Figures 2 and 3 when the two portions of the box therein illustrated are placed in position for commencing the closing procedure.

Figure 5 is a section taken on the line V—V of Figure 4.

Figure 6 is a section taken on the line VI—VI of Figure 4.

Figure 7 is a section taken on the line VII—VII of Figure 4.

Figure 8 is a section showing the same parts as shown in Figure 4 but in different positions relative to each other.

Figure 9 is a fragmentary detail showing an alternative structure for the pin and pin receiving opening shown in Figures 4 and 8.

This invention comprises essentially a closure for a pair of cooperating rectangular, or other shaped, hollow members having two substantially L-shaped sections which fit together in the manner shown in Figure 1 to form a closed container. These parts may be made of any material, such as wood, with the several pieces firmly glued, or otherwise fastened to each other, or it may be molded from suitable plastic.

One element of the container, which may be either part, but which will be called the top section for purposes of convenience in naming, has a

body 1 perpendicular to a downwardly extending end wall 2. The top may be of any shape, and in the form illustrated includes an arcuate interior. Running longitudinally along the sides of this section, are two pairs of outwardly extending

flanges 3 and 3a projecting over recesses 4, as shown in Figure 5. The flange material is cut out at the midsection of each side to provide the open spaces 5 shown in Figure 6 interposed between the flanges 3 and 3a for purposes appearing hereinafter. On one side of this open portion 5 there is an opening 6 projecting upwardly into the solid portion of the top section as shown in Figure 7 and having its walls 7 slightly converging through all, or at least approximately one half of the inner portion, of its length.

An arcuate space 9 has been provided at one end of this top section to accommodate the head of a safety razor, for which this particular container is designed. This hollowed section, however, is not an essential part of the invention.

The other section of the box, which may be either section, but which will be called the bottom section for purposes of convenience in naming, likewise has a longitudinal body 10, which forms the bottom of the box, and an upwardly extending end wall 11 perpendicular thereto. This section has a substantially arcuate center portion also terminating at each side in recesses 12 over which flanges 13 and 13a project inwardly as shown in Figure 5. These flanges and recesses are of size and shape to interlock with the flanges 3 and 3a and their associated recesses when the container is assembled. The flanges are cut out along the center portion of each side, as seen in Figure 6, for purposes to be shown hereinafter.

Along one side of the bottom section there is provided a cylindrical opening 14 extending into the otherwise solid side portion of said bottom section from the open part 18 at the end thereof. This opening contains a freely moving cylindrical member 15. A rounded peg 16 is immovably attached to the cylinder and projects upwardly through the slot 19 in the manner shown in Figure 7. This cylindrical member is normally held in the position shown in Figure 2 by a spring 17, but may be moved backwardly against the spring when required by the closing or opening operation. The peg is of size to be received easily by the opening 6 in the top section of the container.

Figures 4 and 5 show the bottom and top sections of the container in longitudinal section in two relative positions with respect to each other during an opening or closing operation. The functioning of this box closure can readily be seen therefrom. With the two sections held in the relative positions shown in Figure 4, the top section 1 is moved downwardly until the opening 6 in the top section is entered by the peg 16 of the bottom section. At this point the flanges 13 and 13a in the top section rest upon, or approach close to, the flanges 3 and 3a of the bottom section. In order to engage these two sets of opposing flanges, the top section is then moved longitudinally with respect to the bottom section in a rightward direction as the parts appear in the drawings or backwardly as referred to in the claims. The engaged peg 16 will move the cylindrical member 15 also rightwardly and will cause the spring 17 to compress. As the flanges pass each other and the top and bottom sections are manually urged together they will fall into the positions with respect to each other from which interlocking of their respective flanges and recesses may be effected. When the manual holding is then released from the top section, the spring, acting through the cylindrical member 15 and the peg 16, will force this top section in a closing direction or forwardly as referred to in the claims. Thus the flanges will be carried into engagement the beginning of which is shown in Figure 8 and a closure provided which is simple and effective.

By tapering the inner part of the opening 6 above described there is secured further tightness in the holding function. The need for and purpose of this will be apparent from the following.

As will appear from an inspection of Figure 4 the pin 16 must necessarily be able to enter the

opening 6 from its most forwardly position, which is that position assumed when the container is open. If, however, the opening 6 is made large enough to receive said pin easily, any slight manufacturing variation in the longitudinal position of said opening with respect to said pin will if in one direction make it difficult or impossible to interengage the pin and opening, or if in the other direction it will make said opening loose on said pin when the box reaches its full closed position and permit the parts to remain only loosely engaged. By slanting backwardly in the direction of compression of the spring 17 either the forward wall of the pin or at least an inner part of the forward wall of opening 16, this difficulty is overcome. With the described means so constructed, the pin in its most forwardly position will readily commence to enter the opening 16, but as the pin goes in further it will be pushed backwardly sufficiently with respect to the top member 10 that when it comes forwardly again as the box is closed it will not come quite as far forwardly as the position of the stop. Thus tension of the spring will act constantly to urge the parts together and prevent any looseness. In the particular embodiment disclosed this is secured by slightly tapering the inward portion of said opening. Thus the pin is permitted to enter the opening in one longitudinal position with respect to the top member 10 shown in Figure 4 but when the pin enters all of the way into said opening it will be forced to move slightly to the right with respect to said body 1 from the position as shown in said Figure 4. In this way, when the box is fully closed the pin is moved slightly backwardly against the spring 17 and is held slightly away from the forward end of the slot 19 which acts as a stop for the pin. By this means a constant tension by the spring is held onto the box parts when said parts are in a fully closed position urging them firmly together.

An alternative manner of effecting the same end is shown in Figure 9. Here the opening 6a, corresponding to the opening 6 in the other figures, has straight and parallel sides, and the shifting is provided by beveling the forward side of the pin 16a, which corresponds to the pin 16 in the other figures. Other variations, such as merely rounding the top of the pin or slanting only a forward part of the opening, will be evident to those acquainted with articles of this sort.

In order to open the box, the only movement necessary is again to displace the top of the box rightward with respect to the bottom as the same appear in the drawings sufficiently to disengage the flanges, at which point the top may be completely removed. As the top is removed the peg 16 is released and it, together with the cylindrical member 15, will snap back to its leftward position.

The advantages of this box closure are evident. There are no outside latches or hinges to come loose or to rust, or to disfigure the simplicity of the design of the container; the box may be opened and closed with a single rapid movement, and it is simple to construct this container which may be made from a variety of suitable materials.

Many variations may be made, in addition to those above specifically mentioned, but they will all be included within the scope of my herein-after appended claims except as said claims expressly limit otherwise.

I claim:

1. In a container comprising a pair of coop-

erating members held together in closed position by a plurality of interlocking flanges and movable out of closed position by slidingly disengaging said flanges; closure means cooperating therewith comprising: a pin supported by one of said cooperating members in a direction substantially perpendicular to the line of relative movement between the said cooperating members as the interlocking flanges thereof are engaged and disengaged and movable in container closing direction in response to and in container opening direction against resilient means on a line parallel to said line of relative movement; stop means limiting the movement of said pin in response to said resilient means; an opening in the other of said cooperating members located and aligned to receive said pin at said stop means when said cooperating members are placed together for interlocking; a surface of said pin and a surface defining said opening being inclined with respect to each other in a direction such that the pin will be by such opening defining surface moved against said resilient means as said cooperating members are brought fully together and said pin thereby moves into said opening, such that when said cooperating members are fully interlocked said pin is by at least a portion of the contacting wall of said opening held against the urging of said resilient means, slightly away from said stop means whereby the force of said resilient means is constantly effective in holding said cooperating members in fully interlocked position.

2. In a container comprising a pair of cooperating members held together in closed position by a plurality of interlocking flanges and movable out of closed position by slidingly disengaging said flanges, closure means cooperating therewith comprising: a pin supported by one of said cooperating members as the interlocking flanges thereof are engaged and disengaged and movable in container closing direction in response to and in container opening direction against resilient means on a line parallel to said line of relative movement; stop means limiting the movement of said pin in response to said resilient means; an opening in the other of said cooperating members located and aligned to receive said pin when said cooperating members are interlocked together in container relationship, at least an inner portion of the surface defining said opening against which said pin is urged when it is received therein being inclined in a direction opposite to the direction of said urging sufficiently that when said cooperating members are fully interlocked said pin is by said inclined surface defining said opening held against the urging of said resilient means slightly away from said stop means whereby the force of said resilient means is constantly effective in holding said cooperating members in fully interlocked position.

3. In a container comprising a pair of cooperating members held together in closed position by a plurality of interlocking flanges and movable out of closed position by slidingly disengaging said flanges, closure means cooperating therewith comprising: a cylindrical opening in one of said cooperating members aligned parallel to the direction of relative movement of said cooperating members as the same are engaged with or disengaged from each other; a slide within said opening and resiliently urged in a closing direction; engaging means operatively associated with said slide and extending toward the other

of said cooperating members, stop means limiting the movement of the engaging means in response to said slide; an opening in the other of said cooperating members located in position to receive said engaging means, at least the inner portion of the walls defining said opening being tapered sufficiently that when said cooperating members are fully interlocked said engaging means is by the inner wall of said opening held against movement in response to said slide slightly away from said stop means whereby said resilient urging is constantly effective in holding said cooperating members in fully interlocked position.

4. In a container comprising a pair of cooperating members held together in closed position by a plurality of interlocking flanges and movable out of said closed position by slidingly disengaging said flanges, closure means cooperating therewith comprising: a cylindrical opening in one of said cooperating members aligned parallel to the direction of relative movement of said members as the same are engaged and disengaged with respect to each other; a cylindrical slide within said opening and urged in a closing direction by resilient means, engaging means associated with said cylindrical member and extending toward the other of said cooperating members in a direction substantially perpendicular to the line of relative movement between the said cooperating members as the interlocking flanges thereof are engaged and disengaged; stop means limiting the movement of said engaging means in response to said resilient means; an opening in the other of said cooperating members located and aligned to receive said engaging means when said cooperating members are interlocked together in container relationship, at least the inner portion of the walls defining said opening being tapered sufficiently that when said cooperating means are fully interlocked said engaging means is by the inner wall of said opening held against the urging of said resilient means slightly away from said stop means whereby the force of said resilient means is fully effective in holding said cooperating members in fully interlocked position.

5. In a container comprising a pair of cooperating members held together in closed position by a plurality of interlocking flanges and movable out of closed position by slidingly disengaging said flanges, closure means cooperating therewith comprising: a cylindrical opening in one of said members aligned parallel to the direction of relative movement of said members as the same are engaged with or disengaged from each other; a cylindrical slide within said opening and urged in a closing direction by resilient means contained within said opening; a pin carried by said cylindrical member and extending therefrom toward the other of said cooperating members in a direction substantially perpendicular to the line of relative movement between the said cooperating members as the interlocking flanges thereof are engaged and disengaged; said pin extending through a slot in one wall of said cylindrical opening and one end of said slot constituting stop means therefor limiting the movement of said pin and cylindrical member in response to said resilient means; an opening in the other of said cooperating members located and aligned to receive said pin when said cooperating members are interlocked together in container forming relationship, at least the inner portion of the walls defining said opening being tapered sufficiently that when said cooperating members are fully in-

7
terlocked said pin is by the inner walls of said opening held against the urging of said resilient means slightly away from said stop means whereby the force of said resilient means is fully effective in holding said cooperating members in fully interlocked position.
